CLAIM

The ornamental design for a connector housing, substantially as shown and described.

DESCRIPTION

FIG. 1 is a front elevational view of a connector housing embodying our new design,

FIG. 2 is a rear elevational view thereof,

FIG. 3 is a top plan view thereof,

FIG. 4 is a bottom plan view thereof,

FIG. 5 is a right side elevational view thereof and a left side elevational view is the mirror image thereof,

FIG. 6 is a cross-sectional view thereof, taken along line VI—VI of FIG. 1;

FIG. 7 is a front elevational view of a connector housing showing our new design according to a second embodiment thereof;

FIG. 8 is a rear elevational view thereof,

FIG. 9 is a top plan view thereof,

FIG. 10 is a bottom plan view thereof,

FIG. 11 is a right side elevational view thereof and a left side elevational view is the mirror image thereof,

FIG. 12 is a cross-sectional view thereof taken along line XII—XII of FIG. 7.

FIG. 1

FIG. 2

FIG. 3

FIG. 4

FIG. 5

FIG. 6

FIG. 7

FIG. 8

FIG. 9

FIG. 10

FIG. 11

FIG. 12
